CARBURETOR

Emil O. Wirth, South Bend, Ind., assignor to
 Bendix Products Corporation, South Bend,
 Ind., a corporation of Indiana

Application May 1, 1937, Serial No. 140,075

8 Claims. (Cl. 261—72)

This invention relates to carburetors and more particularly to carburetors for forming a combustible mixture of fuel and air for internal combustion engines.

5 Difficulty has heretofore been encountered in carburetors due to boiling of the fuel in the fuel chamber caused by heating of the carburetor parts during engine operation, and in the nozzle due to drop of pressure at the metering orifice. 10 This effect is particularly pronounced with fuel containing an appreciable percentage of low boiling point constituents and interferes with proper metering of the fuel, thereby making it extremely difficult to maintain a proper fuel-air mixture.

15 One of the objects of the present invention is to provide a carburetor in which fuel is metered accurately without interference due to boiling. Preferably the fuel is fed to the nozzle from the lower part of a fuel chamber and a current of air is passed across the surface of the fuel in the chamber to remove the more volatile constituents, the current of air being then conducted into the carburetor mixture conduit adjacent the inlet end thereof.

20 Other objects, advantages and novel features of the invention will be apparent from the following description when read in connection with the accompanying drawing, in which:

25 Figure 1 is a central section with parts in elevation of a carburetor embodying the invention; and

Figure 2 is a similar partial view of a modified construction.

The illustrated carburetor comprises a conduit or induction passage 10 constricted at 12 to form a venturi and having a choke valve 14 and a throttle valve 16. A fuel chamber is formed around the central portion of the conduit 10 and preferably includes a body portion 18 formed integral with the lower part of the conduit and a cover 20 formed integral with the upper part of the conduit. The cover 20 and body 18 as well as the two parts of the conduit 10 are connected in a horizontal plane adjacent the upper part of the fuel chamber and above the normal fuel level therein with a gasket 22 between them. Suitable means are provided to maintain the level of fuel in the fuel chamber substantially constant, such means as shown comprising a float 24 operating a valve 26 which controls inlet of fuel into the fuel chamber from a pipe 28. The pipe 28 may connect to a fuel pump, a tank or any other suitable source of supply.

Fuel from the fuel chamber is supplied to the conduit 10 through a nozzle 30 opening into the

lower part of the fuel chamber through a metering orifice 32 and discharging into a primary venturi 34 arranged centrally of the venturi 12. The central portion of the nozzle 30 is formed with a series of bleed openings communicating with a chamber 36 which is connected to the inlet end of the conduit 10 by a tube 38. Thus air is bled into fuel passing through the nozzle and a mixture of fuel and air is discharged into the venturi 34 to be mixed with air flowing there- 10 through.

Air is supplied to the upper end of the conduit 10 through an air cleaner indicated generally at 40. The illustrated air cleaner is of a known commercial type including a body of oil or the like 42 over which the air sweeps and a filter mass 44 for removing from the air any foreign particles carried thereby. The cleaned air passes from the filter mass downwardly through a central discharge tube 46 into the upper end of the conduit 10. It will be understood that the carburetor is not restricted to use with the particular air cleaner illustrated but that any other suitable type of cleaner could be employed or that the carburetor could be used without any air cleaner. 25

With a carburetor as so far described it has been found that difficulty may be encountered in properly metering the fuel due to boiling of the fuel in the float chamber and nozzle, this difficulty being particularly pronounced when the carburetor is mounted closely adjacent a hot part of the engine and when so-called "winter gasoline" containing a high percentage of volatile constituents is used. This difficulty is overcome according to the present invention by removing most of the highly volatile constituents prior to metering of the fuel through the orifice 32 and prior to entry of the fuel into the nozzle so that correct proportions of fuel and air are maintained at all times. The volatile constituents are preferably drawn off through openings 48 in the gasket 22 and through a passage 50 into the inlet end of the conduit 10 where they are mixed with air and led into the engine. The openings 48 are staggered with respect to the passage 50 to prevent fuel from splashing up into the passage and being drawn into the conduit 10. A short tube 52 is connected to the passage 50 and projects into the conduit 10 and opens generally in the direction of incoming air to be subject to the impact effect thereof. This reduces the suction effect on the passage 50, due to the restricting or choking effect of the air cleaner, which suction tends to become too high at high air flows, and the arrangement thus tends to maintain a sub- 50 55

stantially constant suction on the passage 50 at all times. The tube 52 also projects out toward the center of the air stream which may be somewhat constricted by the tube 46 of the air cleaner 5 so that the impact thereon is representative of the true air flow condition. Tube 52 opens into the induction passage anterior to the choke valve 14, since otherwise closing of the choke valve would put the fuel chamber under a suction 10 equal to that exerted on the nozzle 30 when the choke valve is closed, so that no enrichment of the mixture would be accomplished.

Passage 50 is provided with a restricted opening 53 to the atmosphere, which reduces the effective suction transmitted from tube 52 to the fuel chamber and also tends to prevent any liquid fuel which may be drawn into the lower end of passage 50 from being drawn upwardly into the induction passage.

20 In order to reduce the suction in the fuel chamber (caused by the resistance of the air cleaner to the flow of air therethrough) and to provide a current of air to sweep away the volatilized constituents, an air inlet is provided at the opposite side of the fuel chamber from the passage 50. The air inlet may be formed by a short tube 54 secured to the cover 20 and opening into the fuel chamber through a hole or series of holes 56 in the gasket 22. The holes 56 and tube 54 are 25 preferably offset to prevent fuel from splashing out the tube and a cap 58 may be provided to keep dirt away from the inlet end of the tube.

The air inlet opening provided by the tube 54 is preferably so proportioned with respect to the 30 passage 50 that a pressure drop of approximately $\frac{3}{8}$ inch of water will exist between the tube and passage during the time the engine is in operation. This means that the fuel chamber will be subjected to a substantially constant suction 35 which will assist in vaporizing the more volatile constituents of the fuel but which is not enough to cause vaporization of those constituents which will flow through the orifice 32 and the nozzle without boiling.

40 In order to conduct away from the engine any vaporized fuel which boils out the fuel chamber after the engine is stopped to prevent "flooding" of the engine or danger of fire, the upper end of tube 54 is disposed at a lower level than that of the tube 52, and in addition tube 54 may, if desired, be provided with a drain pipe 60 leading downwardly to a point remote from the engine. Since the vapor is heavier than air it will flow 45 through the pipe 60 to such remote point where it cannot interfere with engine operation nor create a possibility of fire or explosion when the engine is restarted.

When an air cleaner is used it creates a variable resistance to the flow of air into the carburetor due to the fact that its filter mass may be dry at one time and wet at another. This causes a variable choking effect on the carburetor 50 tending to increase the richness of the mixture but since the passage 50 is responsive to suction at the air cleaner outlet any choking effect produced by the air cleaner is reflected in increased suction in the fuel chamber which tends to decrease the richness of the mixture. By properly proportioning the effective cross sections of passage 50, tube 54, and opening 53, these two effects can be made substantially to 55 cancel each other so that the richness of the mixture is not responsive to variations of flow resistance in the air cleaner.

75 Figure 2 illustrates a modified construction,

parts therein corresponding to like parts in Figure 1 being designated by the same reference numerals plus 100. In this construction the tube 154 extends into the conduit and opens in the direction of incoming air, the choke valve 114 5 being provided with a slot 115 through which the tube 154 extends when the valve is closed. The tube 152 is reversed from the position shown in Figure 1 and opens in the direction of air flow so that it is not subject to impact of the 10 incoming air. The pipe 160 is connected to the tube 154 below the level of the tube 152 to conduct away vapor when the engine is stopped and is of relatively small diameter so that it will not interfere with the balance between tubes 15 152 and 154.

In the usual automobile construction the engine is located in front under a hood, into which air flows through the radiator, and at high speeds the impact of this air flow raises the 20 pressure under the hood as much as two inches of water above atmospheric. The herein disclosed system of drawing vapor from under the hood through the float chamber and thence into the mixture conduit may be employed and 25 be so proportioned to maintain the float chamber at atmospheric pressure or slightly sub-atmospheric pressure so that a substantially uniform pressure is maintained in the float chamber over the wide range of vehicle speeds, and 30 particularly at high speeds during which the pressure under the hood would ordinarily tend to enrich the mixture by the increased pressure in the float chamber.

Due to the difference in pressure on the 35 tubes 152 and 154 created by the air flow, air will be circulated through the tube 154, across the float chamber, and through passage 150 and tube 152 back to the conduit. The pressure drop between the two tubes can be controlled 40 by proportioning the tube sizes and the angles of their opening to maintain substantially any desired amount of suction in the fuel chamber. Also any fluctuations in suction due to varying 45 resistance in the air cleaner will be communicated to the fuel chamber through both tubes 152 and 154 and will compensate for the choking effect of the air cleaner.

While two embodiments of the invention have been shown and described, it will be apparent 50 that many changes might be made therein and it is not intended to limit the scope of the invention to the forms shown nor otherwise than by the terms of the appended claims.

What is claimed is:

1. A carburetor comprising an induction passage, a choke valve in the inlet end of the induction passage, a fuel chamber, a fuel nozzle connected to said fuel chamber and discharging into the induction passage posterior to the choke valve, 60 tubes projecting into the induction passage anterior to the choke valve when said valve is in a closed position and opening in opposite directions relative to the direction of air flow, and means connecting said tubes with opposite 65 sides of said fuel chamber.

2. A carburetor comprising a choke valve, an induction passage, a fuel chamber, a nozzle connected to the fuel chamber and discharging into the induction passage, a pair of conduits 70 leading from substantially spaced points in the top of the fuel chamber to the induction passage anterior to the choke valve, one of said conduits opening in one direction and the other opening in the other direction, and a pipe con- 75

nected to one of said conduits below the point at which they communicate with the induction passage to conduct away heavier-than-air fuel vapor.

5. 3. In a plain tube carburetor comprising a downdraft induction passage adapted to receive an air cleaner at the entrance thereof, a choke valve in the induction passage, a constant level fuel chamber supplying fuel to the induction passage posterior to said valve, a conduit leading from the fuel chamber above the fuel level thereof and opening into the induction passage anterior to the choke valve when said valve is in a closed position, a vent tube having an atmospheric inlet and having an outlet in the fuel chamber above the fuel level thereof and at a point substantially spaced from the inlet to said conduit, said conduit including a tube projecting into the induction passage and opening upwardly toward the induction passage inlet to thereby be subjected to but a moderate depression during periods of operation for creating a draft of air across the surface of the fuel in the fuel chamber, and a baffle disposed above the fuel level of said fuel chamber to prevent liquid fuel from entering the conduit and tube.

4. In a plain tube carburetor comprising an induction passage, a choke valve therein, a constant level fuel chamber supplying fuel to the induction passage, a conduit having an inlet at one side of the fuel chamber above the fuel level thereof and having an upwardly opening outlet in the induction passage anterior to the choke valve when in closed position, a vent tube leading from a source of substantially atmospheric pressure to the other side of the fuel chamber above the fuel level thereof, means for creating a depression at the outlet of said conduit to thereby induce a moderate draft of air across the surface of the fuel in the fuel chamber, and a discharge tube leading from the vent tube to a point remote from the carburetor to conduct away heavier-than-air fuel vapor when the carburetor is not in operation.

5. A carburetor comprising a downdraft induction passage, a choke valve therein, a fuel chamber, a nozzle connected to the fuel chamber and discharging into the induction passage, a conduit having an inlet in the top of the fuel chamber at one side thereof and having an upwardly opening outlet in the induction passage anterior to the choke valve, a vent tube having an air inlet and having an outlet in the top of the fuel chamber at the opposite side thereof, and means for creating a depression on said conduit outlet during operating periods to draw fuel vapors into the induction passage from above the surface of the fuel in the fuel chamber and to create a draft of air across said surface to thereby permit additional fuel to vaporize.

6. A carburetor comprising a downdraft induction passage, a choke valve therein, a fuel

chamber below the upper end of said induction passage, a nozzle connected to the fuel chamber and discharging into the induction passage posterior to the choke valve, an air vent opening from atmosphere into the top of the fuel chamber, a vapor conduit leading from the top of the fuel chamber at a point remote from the air vent and opening into the upper end of the induction passage anterior to the choke valve when closed, said vapor conduit including a tube projecting into the induction passage and opening upwardly toward the induction passage inlet, means creating a depression at the outlet of said tube during periods of operation to thereby draw fuel vapors into the induction passage from above the surface of the fuel in the fuel chamber and to create a draft of air across said surface to permit additional fuel to vaporize, and an atmospheric vent in said vapor conduit to partially satisfy the depression therein.

7. A carburetor comprising a downdraft induction passage, a choke valve therein, a fuel chamber below the upper end of the induction passage, a fuel nozzle connected to the fuel chamber and discharging into the induction passage, a vent tube having an air inlet and leading into the top of the fuel chamber at one side thereof, a conduit leading from the top of the fuel chamber at the opposite side thereof and having an outlet in the upper end of the induction passage anterior to the choke valve, means for creating a lower pressure at said conduit outlet than at said air inlet during periods of operation to thereby create a draft of air across the surface of the fuel in the fuel chamber, and a pipe connected to the vent tube at an elevation lower than either the conduit outlet or the air inlet and leading to a point remote from the carburetor.

8. A carburetor comprising a downdraft induction passage, a choke valve therein, a fuel chamber formed with a lower body portion and a cover adapted to be connected in a substantially horizontal plane above the normal fuel level, a nozzle connected to said fuel chamber and discharging into the induction passage, said cover being formed with an air vent opening, a vapor conduit leading from said cover at a point substantially spaced from said air vent opening and having an outlet in the induction passage anterior to said choke valve, means creating a depression in the induction passage anterior to the choke valve during operation to thereby induce a flow of air and fuel vapor from said outlet, and a gasket between the body portion and cover formed with openings to establish communication between the body portion and the vent and vapor conduit, said openings being so arranged as to form a tortuous passage through the fuel chamber from the vent to the vapor conduit thereby to prevent fuel from splashing out the vent or the vapor conduit.
